UNITED STATES PATENT OFFICE.

IRWIN ROTTENBERG, OF NEW YORK, N. Y.

YARN ANCHOR FOR KNITTING MACHINES.

Application filed April 26, 1928. Serial No. 272,870.

My present invention relates generally to knitting machines, and has particular reference to a yarn anchor for use with knitting machines which are constructed and arranged 5 for knitting striped fabrics.

Before describing my invention in detail, I will premise that in the knitting of striped fabrics wherein the stripes are transverse to the fabric, one or more sets of thread guides 10 are provided in association with means for automatically rendering a predetermined one of each set operative at predetermined times and the others of said set inoperative. For 15 the purpose of explaining the nature of my present invention, I have herein illustrated and I shall hereinafter refer to a knitting machine wherein a single set of such thread guides is provided. Furthermore, I have, 20 for purposes of simplification, described and shall hereinafter refer to said set of thread guides as comprising only two individual thread guides, one thereof being adapted to feed a thread of one color, and the other thereof being adapted to feed a thread of 25 another color.

My invention has particular reference to a knitting machine of the rotating type, i. e., one wherein a set of needles are arranged along a closed arcuate path, and wherein 30 one or the other of said thread guides is made to move along said path and in operative relationship to said needles, thereby incorporating the particular thread guided thereby spirally into the fabric being knitted. The 35 latter comprises a tubular construction constantly growing in length as one or the other thread is laid and knitted spirally in association with one edge of said tubular structure.

In a simplified knitting machine of the 40 character above referred to, one or the other of the thread guides is operated to lay the guided thread into operative association with the needles, and the other thread guide is at the same time shifted so as to travel in an 45 inoperative path wherein the thread guided thereby is made to float.

It is an object of my present invention to provide a yarn anchor which will automatically engage said floating thread, tension the 50 same in a prompt and efficient manner, and

thereupon cut the same at a point closely adjacent to the point at which said thread commences to float. In the absence of any yarn anchor whatsoever, it will be understood that the floating thread will form a useless loop 55 extending from the point at which the thread commences to float to the point at which it is again led into association with the knitted fabric. Such loop will be large or small, depending upon the length of time that the 60 other or operative thread is being knitted into the fabric. Where a number of sets of thread guides are employed, usually four, and where each set comprises say four, instead of two, thread guides, the number of loops which 65 would thus be formed are considerable, and since they vary in lengths and are totally useless so far as the fabric is concerned, they constitute a source of great annoyance, endangering the smooth continuation of the 70 knitting, and necessitating in any event a subsequent manual cutting operation which consumes considerable time and labor.

One of the main objects of my invention is to provide a yarn anchor having the features 75 outlined above and being constructed in such a simple manner as to be extremely inexpensive from a manufacturing standpoint and at the same time highly efficient in operation.

In a machine of the character outlined 80 above, the thread guides are caused to move along the closed path mentioned by a rotating supporting structure mounted upon a rotating shaft. Said shaft is obviously substantially concentric with the tubular fabric 85 being knitted, and the end of said shaft customarily terminates at a point slightly in advance of the edge of the fabric in course of manufacture.

One feature of my invention lies in providing a yarn anchor which is provided with means for simply yet efficiently attaching it to the end of said shaft, said anchor including a metallic collar or the like adapted to be engageable over said end and provided 95 with simple means such as a set screw for attaching it to said shaft.

Another feature of my invention lies in providing a yarn anchor which includes a 100 yarn-engaging hub of extremely simple con-

struction and provided with a set of simple, compact corolliform fingers.

Another feature of my invention lies in providing radial arms upon said hub, said arms being provided at their ends with cutting instrumentalities such as ordinary razor blades. Such arms are so arranged as to serve the added function of preventing the yarn which winds itself around the fingers from slipping off of the latter. In this way, the yarn is promptly tensioned in anticipation of the cutting action of the knives or cutters.

Pursuant to my object relating to simplicity of construction and manufacture, it is a particular feature of my invention to construct my yarn anchor in such a manner that two simple angle members comprise at one time the hub referred to, the means for supporting the fingers, and the radial arms carrying the cutters. More particularly, I provide two oppositely arranged angle members, each one thereof having a portion attached to the collar and extending substantially parallel to the shaft, and a second portion extending radially and constituting one of said radial arms. At the same time, I provide the corolliform fingers of two U-shaped members, each of which has the arms of the U diverging toward the ends thereof and each of which is attached as by means of a simple rivet or stud to one of the angle members.

For the attainment of the foregoing objects and such other objects as may herein-after appear or be pointed out, I have constructed a device embodying the features of my invention and illustrated in the accompanying drawings in which—

Figure 1 is an elevational view, partly in cross-section, showing a yarn anchor of the present character associated with a simplified knitting machine embodying one set of two thread guides;

Figure 2 is a view similar to Figure 1 omitting all parts unessential to a diagrammatic representation of the operation of my device;

Figure 3 is a view similar to Figure 2 showing a further step in the course of knitting and the operation of my device at such time; and

Figure 4 is an enlarged perspective view of the yarn anchor itself.

Referring to Figure 1, I have shown a knitting machine wherein a vertically arranged shaft 10 has a supporting structure 11 mounted thereon. The latter usually carries four spaced sets of thread guides, but in the illustrated embodiment, I have shown a single set designated generally by the reference numeral 12. The unit 12 is carried by the supporting structure 11, and when the shaft 10 rotates, the unit 12 travels through a circular path. Traveling with the unit 12 are the 65 yarn bobbins 13, 14, and 15. In the unit 12

which I have illustrated, I have provided two thread guides 16 and 17. Each of these guides is pivoted adjacent to its upper end so as to be removable from the operative position occupied by the guide 17 into the inoperative position occupied by the guide 16. The guide 16 feeds the thread 18 from the bobbin 14 to the upper peripheral edge of the tubular fabric 19 being knitted; and the guide 17 feeds the thread 20, of a different color from the thread 18, from the bobbin 13 to said peripheral upper edge. In Figure 1, the guide 17 is positioned so that when the unit 12 rotates, the thread 20 will be incorporated into the knitted fabric, the guide 16 being in a position which renders it temporarily inoperative. The mechanism for rendering one or the other of the guides 16 and 17 operative or inoperative at predetermined times is designated generally by the reference numeral 21. 80 This mechanism is fixed and does not rotate, and is operated automatically at predetermined times to interpose the cam 22, the plunger 23 and other instrumentalities into such position with respect to the unit 12 that at predetermined times, as the unit 12 passes the mechanism 21, one or the other thread guides 16 or 17 is thrown outwardly into the inoperative position occupied by the guide 16, while the other thread guide is brought inwardly into operative position. The nature of my present invention does not necessitate a detailed description of the mechanism 21 nor of the manner in which it operates at predetermined times upon the rear portion of the 100 unit 12 to effect such predetermined adjustments of the guides 16 and 17.

Arranged substantially along the path traveled by the operative guide are a set of needles (not shown), these needles being automatically operated in a successive manner so that as the unit 12 lays one or the other thread 18 or 20 into operative relationship with said needles, the latter engage said thread and incorporate it into the fabric 19. For example, a rotation of the device shown in Figure 1 would cause an incorporation of the thread 20, in a spiral manner, with the tubular fabric 19.

Referring for the moment to Figure 4, it will be seen that I have provided a yarn anchor which comprises a collar 24 provided with a set screw 25, the collar 24 being engageable over the end of the shaft 10, as shown in Figure 1, the set screw 25 serving to hold it in position. Extending from opposite sides of the collar 24 are two angle members 26 and 27, each thereof comprising a portion 28 which extends substantially parallel to the shaft to which the collar 24 is to be attached, and a portion 29 extending radially with respect to said shaft. At the end of each of the radial arms 29 I have provided means for mounting a cutting instrumentality such as the ordinary razor blade 130

30. In the illustrated embodiment, I have provided a turned-down portion 31 upon the end of the arm 29, and I have provided a stud or screw 32 which is adapted to pass through 5 one of the openings in the razor blade 30 for attaching the latter to the portion 31. Obviously, the blades 30 are arranged in planes which are perpendicular to the radii, so that as the yarn anchor rotates after attachment 10 to the shaft 10, the cutting edges 33 of the blades 30 will operate to sever any thread or threads which may extend across their circular path of travel. Such cutting action will be extremely effective, particularly if the 15 thread or threads encountered are slightly tensioned.

On each one of the arms 29, adjacent to the portions 28, I have mounted a U-shaped member 34, preferably of relatively light and 20 bendable metal. Each member 34 has arms 35 which are bent into outwardly curved and upwardly divergent positions as illustrated, the four fingers thus provided constituting a yarn-engaging hub of extremely efficient 25 character. These fingers are arranged like the corolla of a flower, as will be readily observed.

In operation, the device of Figure 4 is attached to the shaft 10 as shown in Figure 1, 30 the hub portion lying substantially in the plane of the upper periphery of the tubular fabric 19, and the arms 29 being so arranged as to position the blades 30 slightly within the end of the tubular fabric 19. The yarn 35 anchor obviously rotates with the shaft 10, and hence with the structure 11, the unit 12, and the bobbins 13, 14, 15, etc.

In Figure 1, the mechanism 21 has just been effective to throw out the guide 16 and to draw 40 in the guide 17. In other words the thread 18 has just completed a spiral incorporation with the fabric 19, and it is now contemplated that the differently colored thread 20 will take its place and thereby provide a band or 45 stripe in the fabric. Referring for the moment to the thread 18 alone, I have shown in Figure 2 how this thread will have engaged itself about the fingers 35 after one complete rotation of the unit 12 and the other parts 50 which rotate with it. It will be noted that the thread extends from the point 36, where it commenced to float, around the fingers 35 and back to the thread guide 16, thence upwardly through said guide to the bobbin 14. The point 36 is below the upper periphery 55 of the fabric 19 for the reason that a spiral layer has been knitted upon this periphery during the rotation referred to. The point 60 36 has been illustrated at a point considerably below the periphery of the point 37 because the usual machine embodies four units 12, all operating simultaneously at spaced positions of approximately 90°, and the distance 65 between the point 36 and the periphery 37 is

therefore equal to the space occupied by four knitted layers.

Although the lower portion of the loop illustrated in Figure 2 may be encountered by the blade 30, nevertheless the probabilities 70 are that the point 36 is still not sufficiently low to have the blade 30 operate upon this encountered strand. Moreover, this strand is relatively loose and it will probably ride over the top of the blade 30 even though it be encountered. 75

Still referring to the thread 18, I have shown in Figure 3 how a second complete rotation of the unit 12 will not only drop the point 36 by a further distance as illustrated 80 in this figure, but will also cause the thread 18 to wind itself once more around the fingers 35. This winding will be effective to tension the thread 18 sufficiently so that when the blade 30 encounters the lower portion of 85 this loop it will sever the latter. In Figure 3, the lowermost strand 18 is about to be severed by the blade 30. It will be noted that this severance occurs very close to the fabric itself, thereby leaving a small unobjectionable end 38 extending from the fabric at the point where the strand 18 has completed its incorporation as a stripe in the fabric. The other portion 39 of the strand 18 about to be 90 cut in Figure 3 will dangle from the hub in an unobjectionable manner. This dangling end will continue to extend around the hub and upwardly through the guide 16 to the bobbin 14. No more thread will be drawn from the bobbin 14, however, no matter how many rotations are made, since the 95 yarn anchor rotates with the guide 16.

When the thread 18 is again desired as a color in the fabric, the guide 16 will be drawn inwardly into the position occupied 100 by the guide 17 of Figure 1, and the upper portion 18 illustrated in Figure 3 will then occupy the position of the strand 20 of Figure 1.

Referring now to the strand 20 by itself, 110 it will be noted that it extends from the bobbin 13 through the guide 17, thence inwardly to the hub of the yarn anchor, around the latter, and down to a dangling end which was previously produced in the same manner as the end 39 of Figure 3.

As the unit 12 rotates, the needles will 115 engage the thread 20 which is laid into co-operation therewith by the rotating guide 17. After the guide has made one complete revolution as shown in Figure 2, the strand 20 will have become sufficiently tensioned to be cut by the knife 30. It is to be noted that this strand is not the one which corresponds to the lower strand 18 of Figure 3, but the one which corresponds to the upper strand 18 of Figure 3. As a result of its severance, 120 a loose piece of yarn will extend around the hub and thence down to two dangling ends, 125 as shown in Figure 3. When the thread 18 130

is again thrown into operation, the upper portion of the strand 18 in Figure 3 will be cut in a similar manner so as to produce with the end 39 a second dangling end corresponding to the two loose ends 20 of Figure 3.

I have pointed out in the preceding paragraph that the strand 20 of Figure 2 is sufficiently tensioned to be cut by the knife 30. If only two thread guides 16 and 17 were employed as in the illustrated embodiment, it is quite possible that the tension of this strand 20 would be insufficient. In actual practice, however, as pointed out hereinafter, there are about four thread guides to each 15 of four units similar to the unit 12. Accordingly, the jumble of the loose strands around the fingers 35 has always proven sufficient to tension the strands corresponding to the strand 20 in Figure 2.

As a result of the foregoing operations, a minimum of thread is wasted, since only one or at most two or three windings about the hub are necessary in order to tension the thread sufficiently to be severed by the rotating knife. The reason why the thread is tensioned sufficiently in such few rotations is that the arms 29 prevent the thread which is wound around the fingers 35 from slipping off the lower ends of such fingers. The 25 divergent arrangement of the fingers assures the proper winding of the thread around the hub, and has a definite tendency to position the threads downwardly, but obviously, it can position them no further than 30 the arms 29. As a result, the loops which would otherwise be formed are promptly severed in an efficient manner at points relatively close to the fabric itself.

Although I have illustrated merely one set 40 of guides 16 and 17, and have shown said set as comprising merely the two thread guides 16 and 17, the actual operation of my device is generally accompanied by four or more units 12, each of which embodies four or 45 more different thread guides. Accordingly, when my device is employed, the knives 30 are successively operable upon the strand or strands which are successively tensioned sufficiently and positioned properly to be operatively encountered thereby. During the 50 manufacture of striped fabrics, there is no pulling upon the fabric at the points where the different colors end and commence, since the loops have been promptly cut before any 55 such pulling would become dangerous; and although the hub gradually collects a mass of loose ends, it never amasses enough of them to form an objectionable and possibly dangerous jumble. Nor are any ends 60 dropped by the anchor into the tubular fabric itself. Whatever ends there are are closely wound together around the fingers 35 and are retained in such condition until such time as the anchor may be removed and 65 the mass of threads taken therefrom.

Although I have illustrated and described a device employing razor blades as the cutting instrumentalities, nevertheless it will be understood that such a showing has been made merely to explain the efficient nature 70 of my invention, and I do not mean to limit myself to the employment of such cutting instrumentalities, nor do I mean to limit myself in the appended claims to any particular construction of fingers 35 or arms 29, unless the context calls for such an interpretation. Although the construction illustrated and described is therefore merely illustrative of my invention, nevertheless I have found it extremely satisfactory and efficient both from 75 a manufacturing standpoint and from an efficiently operating standpoint. Where the yarn anchor is to be adapted to different sized knitting machines, I sometimes provide the arms 29 with adjusting means for rendering them extensible. In this way, blades 30 may be adjusted at greater or less distances from the shaft 10, depending upon requirements.

In general, it will be obvious that many changes in the details herein described and illustrated for the purpose of explaining the nature of my invention may be made by those skilled in the art without departing from the spirit and scope of the invention as expressed in the appended claims. It is therefore intended that these details be interpreted as 95 illustrative and not in a limiting sense.

Having thus described my invention and illustrated its use, what I claim as new and desire to secure by Letters Patent is—

1. In a knitting machine, the combination with a rotating thread guide, a set of knitting needles arranged along the arcuate path of travel of said guide and adapted to engage said thread to incorporate it into the fabric 105 being knitted, and means for shifting said guide at predetermined times out of cooperative relationship to said needles so that said thread floats and remains unengaged by said needles during the further rotation of said guide, of a yarn anchor coaxially mounted 110 for rotation with said guide and provided with means for grasping, tensioning, and promptly cutting said unengaged thread at a point relatively close to the point at which 115 it commences to float, said anchor comprising radial arms provided with cutters at their extremities and hence adjacent to the fabric being knitted.

2. In a knitting machine, the combination with a rotating thread guide, a set of knitting needles arranged along the arcuate path of travel of said guide and adapted to engage said thread to incorporate it into the fabric 120 being knitted, and means for shifting said guide at predetermined times out of cooperative relationship to said needles so that said thread floats and remains unengaged by said 125 needles during the further rotation of said guide, of a yarn anchor coaxially mounted 130

- for rotation with said guide and provided with means for grasping, tensioning, and promptly cutting said unengaged thread at a point relatively close to the point at which 5 it commences to float, said anchor comprising a set of corolliform fingers arranged adjacent to the axis of rotation, and radial arms extending from said fingers and provided with blades at their extremities.
- 10 3. In a knitting machine, the combination with a rotating thread guide, a set of knitting needles arranged along the arcuate path of travel of said guide and adapted to engage said thread to incorporate it into the fabric 15 being knitted, and means for shifting said guide at predetermined times out of cooperative relationship to said needles so that said thread floats and remains unengaged by said needles during the further rotation of said 20 guide, of a yarn anchor coaxially mounted for rotation with said guide and provided with means for grasping, tensioning, and promptly cutting said unengaged thread at a point relatively close to the point at which 25 it commences to float, said anchor comprising radial arms provided with cutters at their extremities and hence adjacent to the fabric being knitted, and means for adjusting the positions of said cutters on said arms.
- 30 4. For association with the end of a rotating knitting machine shaft of the character described, a yarn anchor comprising a hub, means for attaching the hub to said shaft end, corolliform fingers carried by said hub, radial 35 arms extending from the converged ends of said fingers, and cutters carried on the ends of said arms.
5. For association with the end of a rotating knitting machine shaft of the character described, a yarn anchor comprising a hub, means for attaching the hub to said shaft end, corolliform fingers carried by said hub, radial arms extending from the converged ends of said fingers, and cutters carried on the ends of said arms; said hub including a 45 collar engageable over said shaft end, and said hub and arms including a pair of angle members each of which has one portion attached to said collar and a second portion constituting one of said arms.
6. For association with the end of a rotating knitting machine shaft of the character described, a yarn anchor comprising a hub, means for attaching the hub to said shaft end, corolliform fingers carried by said hub, radial arms extending from the converged ends of said fingers, and cutters carried on the ends of said arms; said hub including a 55 collar engageable over said shaft end, said arms including a pair of angle members carried by said collar, each of said members having a portion extending substantially parallel to the shaft, and said fingers including a 60 pair of U-shaped members carried by said 65
- angle members respectively adjacent to the parallel portions thereof.
7. For association with the end of a knitting machine shaft of the character described, a yarn anchor comprising a hub, means for 70 attaching the hub to said shaft end, radial arms extending from said hub, cutters at the ends of said arms, and corolliform fingers carried by said hub adjacent to the axis thereof, said fingers including a pair of U-shaped 75 members carried by two of said arms respectively, the arms of each of said U-shaped members diverging toward the ends thereof.
8. A yarn anchor of the character described 80 comprising a hub, a pair of arms extending radially from said hub, knives mounted on the ends of said arms, and a set of corolliform fingers attached to the hub adjacent to the axis thereof.
9. A yarn anchor of the character described 85 comprising a hub, a pair of arms extending radially from said hub, knives mounted on the ends of said arms, and a set of corolliform fingers attached to the hub adjacent to the axis thereof, said fingers including a pair of 90 U-shaped members medially attached to said arms and having the legs of said U's divergently shaped.
10. As a new article of manufacture, a yarn anchor of the character described, comprising 95 a collar, a pair of angle members attached thereto, each of said members comprising a portion substantially parallel to the axis of said collar and a portion extending radially therefrom, and means at the ends of said radial portions for accommodating cutters.
11. As a new article of manufacture, a yarn anchor of the character described, comprising 100 a collar, a pair of angle members attached thereto, each of said members comprising a portion substantially parallel to the axis of said collar and a portion extending radially therefrom, means at the ends of said radial portions for accommodating cutters, and a pair of U-shaped finger members carried by 110 said angle members respectively adjacent to said parallel portions.
- In witness whereof, I have signed this specification this 6 day of April, 1928.
